UNITED STATES PATENT OFFICE.

DANIEL S. GEISER, OF WAYNESBORO, PENNSYLVANIA.

LOCK.

1,368,713.

Specification of Letters Patent. Patented Feb. 15, 1921.

Application filed August 6, 1919. Serial No. 315,700.

To all whom it may concern:

Be it known that I, DANIEL S. GEISER, a citizen of the United States, residing at Waynesboro, in the county of Franklin and State of Pennsylvania, have invented certain new and useful Improvements in Locks, of which the following is a specification.

The present invention relates more particularly to knob-operated locks having means whereby the bolt will be actuated upon the turning of the knob, or by the sliding movement of at least a portion of the knob-spindle.

One of the primary objects is to provide a structure that is simple and practical, together with means whereby the bolt can be effectively latched against movement and can also be locked so that it may be released only by a proper key.

In the accompanying drawings:—

Figure 1 is a longitudinal sectional view through the preferred embodiment of the invention.

Fig. 2 is a longitudinal sectional view at right angles to Fig. 1.

Fig. 3 is a cross sectional view on the line 3—3 of Fig. 1.

Fig. 4 is a side elevation of the bolt.

Fig. 5 is a top plan view of the same.

Fig. 6 is a view in elevation of the key-operated holding dog.

Fig. 7 is a front elevation of the same.

Figs. 8 and 9 are detail views of different tumblers that may be employed.

Similar reference numerals designate corresponding parts in all the figures of the drawings.

A portion of a door is illustrated in Figs. 1 and 3, and is designated 10, said door having a circular bore 11 therein to receive the lock.

The said lock consists of a cylindrical casting 12, within which is located a reciprocating bolt 13, the outer end of which is beveled, as shown at 14, and formed to engage in a suitable recess or the socket of a holding plate in a manner well understood. This bolt is provided with a reduced tail-piece 15, and has an elongated opening 16 therethrough, in which is formed a holding shoulder 17. An elongated opening 18 also extends through the bolt at right angles to and intersects the opening 16. For the purpose of projecting the outer end 14 of the bolt, a coiled spring 19 is located in a socket

20 formed in the outer portion of said bolt, said spring bearing at one end against the inner end of the socket, and at its other end against a floating plunger 21 that extends 60 into said socket.

A holding latch is provided, comprising a shaft 22 having an outer handle 23 and provided at its inner end with a rock arm 24. The free end of this arm is adapted to 65 engage in a recessed seat 25 formed in the rear end of the plunger 21, and is also adapted to be moved to a position behind the shoulder 17. The latch therefore performs a double function, in that it can be 70 moved to a position to hold the bolt against retraction and to a position where it constitutes an abutment for the spring 19.

On opposite sides of the door 10 are placed escutcheon plates 26 having inwardly 75 extending nipples 27 that enter openings 28 formed in the barrel or casing 12 of the lock. These plates also have outstanding sleeve portions 29 forming bearing elements for the inwardly extending shanks 30 of 80 knobs 31. The two knobs 31 are connected by a spindle composed of two sections 32 and 33. The section 32 is secured to the knobs 31 by pins 34 and 35, while the section 33 is free from said knobs. These two sections have abutting flat faces, the section 32 being longitudinally slideable on the section 33, but said sections being together rotatable by reason of their abutting flat faces. The section 32 is provided with a shoulder 36 90 adapted to abut against one end of a bell crank lever 37 pivoted within the barrel as shown at 38, the other end of said lever being adapted to engage a shoulder 39 formed within the bolt 13. The other spindle section 33 has outstanding cam portions 40 that bear against shoulders 41 formed on the bolt.

With this construction therefore, if the bolt 13 is free to move, it will be evident that 100 if the inner knob 30 is pushed toward the door, the section 32 will move longitudinally on the section 33 and the shoulder 36 striking the bell crank 37, will cause the latter to swing, thereby engaging it with the shoulder 39 of the bolt, and pushing said bolt inwardly. On the other hand, if either knob is turned, it will turn the section 32 and consequently the section 33, thereby 105 swinging the cam elements 40, which abutting against the shoulders 41, will cause the retraction of the bolt.

Locking means for the bolt is also provided, which can be actuated by a key inserted from either side of the door. To this end, there is a key receiving member 42 rotatably mounted in the barrel at one side of the tail-piece 15, said member having a key receiving slot 43 normally alined with openings 44 formed in the opposite rear portions of the escutcheons. Pivotedly mounted at 45, directly behind the key receiving member 42, is a holding dog 46 adapted to swing between a position behind the tail-piece 15 of the bolt and a position that will permit the passage of said tail piece along- 15 side the dog. Pivoted on the dog 46 is a plurality of tumblers 47, a common pivot pin 48 being preferably employed for all the said tumblers. These tumblers are yieldingly held in predetermined positions by leaf 20 springs 49 carried thereby and bearing against the dog. The tumblers are provided with upstanding finger portions 50 located in position to be engaged by a key placed in the slot 42 when said key is turned, and the dog 25 46, as illustrated more particularly in Fig. 6, is provided with a recess 51 to receive the key. The opposite walls of the recess constitute bearings for portions of such key. A stop rod or pin 52 is located in rear of the 30 rear ends of the tumblers 47, and said tumblers have recesses 53 to receive the same. As will be evident, the tumblers may be constructed in a variety of ways, so that some are normally positioned with their recesses 35 in line with the stop pin 52, while others are out of line, as illustrated in Fig. 2.

With this construction, and with the bolt lock as illustrated in Fig. 2, it will be evident that if the proper key is introduced 40 into the member 42, and turned, the said key will not affect those tumblers which have their recesses 53 alined with the stop pin 52, but will swing those tumblers which have their recesses out of alinement, so as to aline 45 the same therewith, thereupon the key will engage the dog 46 and swing the same until it is out of alinement with the tail-piece 15 and the bolt will be free for operation by the knobs. If an improperly shaped key is introduced, however, it may either fail to 50 move the tumblers that are in locking position, or will move those that are out of locking position into locking position, and thus prevent the movement of the holding dog.

It will be noted that while the holding arm or latch 24 moves downwardly behind the shoulder 17 and the holding dog 46 moves upwardly behind the tail-piece 15, yet the unlocking actions of the operating parts 60 are in the same direction. That is to say, the handle 23 is turned upwardly or clockwise to move the latch 24 to its inactive position and a key inserted in the slot 43 is also moved clockwise to disengage the dog 46 65 from the tail-piece.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention. 75

Having thus described my invention, what I claim as new, and desire to secure by Letters Patent, is:

1. In a lock, the combination with a casing, of a bolt member movably mounted therein, a rotatable spindle member comprising sections located transversely of the casing and both sections projecting therethrough, said sections being relatively slidable in a longitudinal direction, knobs engaged with both sections, and means for effecting the movement of the bolt when one spindle member section is longitudinally slid with respect to the other and also when the sections are simultaneously rotated. 85

2. In a lock, the combination with a casing, of a bolt member movably mounted therein, a spindle member comprising sections both projecting from the casing, a knob inclosing the projecting ends of both sections, one of said sections being slidable with respect to the other, said other section being rotatable, means for effecting said movements on the corresponding movements of the knob, and means for moving the bolt on the sliding movement of one section and the rotary movement of the other section. 95

3. In a lock, the combination with a casing, of a bolt member movably mounted thereon, a spindle member comprising sections both projecting from the casing, one of said spindles being slidable with respect to the other, said sections being together rotatable, a knob having a shank inclosing the projecting ends of both sections, means for effecting said movements on the corresponding movements of the knob, and means for moving the bolt on the relative sliding movement of the sections and the rotary movement of both sections. 105

4. In a lock, the combination with a bolt member, of a spindle member comprising sections, one of which is slidable with respect to the other, said other section being rotatable, a cam portion on one section that effects the movement of the bolt when the spindle is turned, and a lever element interposed between the sliding section and bolt for moving the bolt upon the sliding movement of said section. 120

5. In a lock, the combination with a reciprocatory bolt member, of a rotatable spindle passing therethrough and comprising sections, one of which is longitudinally slidable upon the other, the sections together being 130

5 rotatable, a lever element interposed between the sliding section and the bolt for actuating the latter on the sliding movement of the former, and outstanding cam portions on the other section engaging the bolt to operate the same upon the rotary movement of both sections.

10 6. In a lock, the combination with a bolt, of a transversely disposed spindle comprising relatively movable sections, a knob fastened to one section on one side of the bolt and slidably inclosing the end of the other section, a knob fastened to one of the sections on the other side of the bolt, and slidably inclosing the end of the other section, and means for effecting the movement of the bolt on the sliding movement of one section and upon the rotary movement of the spindle.

15 7. In a lock, the combination with a bolt and means for moving the same in one direction, of a spring for moving the bolt in an opposite direction, and common means for locking the bolt and forming an abutment for the spring.

20 8. In a lock the combination with a bolt and means for moving the same in one direction, of a spring for moving the bolt in an opposite direction, and a lock for the bolt movable between a position to form an abutment for the spring and a position in the path of a portion of the bolt.

25 9. In a lock, the combination with a bolt and means for moving the same in one direction, of a spring for moving the bolt in an opposite direction, a plunger borne against by the spring, and a pivoted locking dog movable between a position behind the plunger and a position in the path of a portion of the bolt.

30 10. In a lock, the combination with a reciprocating bolt having a longitudinal socket, of a coiled spring in the socket bearing against the bolt, a plunger in the socket borne against the spring, and a pivoted locking bolt including an arm movable to a position behind the plunger and a position behind a portion of the bolt.

35 11. In a lock, the combination with a movable bolt, of a holding dog movable into and out of the path of a portion thereof, key-engaged tumblers movably mounted on the dog, and stop means against which the tumblers are adapted to abut to prevent movement of the dog. 55

40 12. In a lock, the combination with a movable bolt, of a pivotally mounted holding dog movable into and out of the path of a portion of the bolt, key-engageable tumblers pivoted on the dog, and stop means against which the tumblers are adapted to abut, to prevent movement of the dog. 60

45 13. In a lock, the combination with a movable bolt, of a holding dog movable into and out of the path of a portion thereof, key-engageable tumblers movably mounted on the dog, and stop means against which the tumblers are adapted to abut to prevent movement of the dog, said tumblers having recesses adapted to receive the stop means and thereby permit the movement of the dog. 65

50 14. In a lock, the combination with a reciprocating bolt, of a holding dog pivoted behind the bolt, and movable into and out of the path of a portion thereof, key-engageable tumblers pivoted on the dog, a rotary key holder located adjacent to the tumblers, and a stop rod located behind the tumblers, said tumblers having recesses adapted to receive the rod and permit the movement of the dog. 75

55 15. In a lock, the combination with a casting, of a reciprocating bolt therein having locking shoulders, a latch movable in one direction to engage behind one of the shoulders, a dog movable in an opposite direction to engage behind the other shoulder, and operating devices for the latch and dog movable in the same direction to move said latch and dog respectively in opposite directions. 80 85 90

In testimony whereof, I affix my signature in the presence of two witnesses.

DANIEL S. GEISER.
